(57) **CLAIM**

The ornamental design for a bathtub, as shown and described.

DESCRIPTION

FIG. 1 is a front perspective view of a bathtub according to the present invention.

FIG. 2 is a left side view of the bathtub of FIG. 1.

FIG. 3 is a right side view of the bathtub of FIG. 1.

FIG. 4 is a top view of the bathtub of FIG. 1.

FIG. 5 is a bottom view of the bathtub of FIG. 1.

FIG. 6 is a front view of the bathtub of FIG. 1; and,

FIG. 7 is a rear view of the bathtub of FIG. 1.

The dashed lines illustrate environment that does not form a part of the present invention, and no claim is made to the material illustrated with dashed lines.

1 Claim, 7 Drawing Sheets

DATED : November 8, 2022
INVENTOR(S) : Flowers et al.

Page 1 of 1

It is certified that error appears in the above-identified patent and that said Letters Patent is hereby corrected as shown below:

On the Title Page

Item (63) shows:

(63) Continuation of application No. 29/769,312, filed on Feb. 4, 2021, now Pat. No. Des. 926,946, which is a continuation of application No. 29/747,233, filed on Aug. 20, 2020, now Pat. No. Des. 912,786, which is a continuation of application No. 29/719,734, filed on Jan. 7, 2020, now Pat. No. Des. 896,931, which is a continuation of application No. 29/706,139, filed on Sep. 18, 2019, now Pat. No. Des. 875,903, which is a continuation of application No. 29/679,571, filed on Feb. 7, 2019, now Pat. No. Des. 866,725, which is a continuation of application No. 29/625,115, filed on Nov. 7, 2017, now Pat. No. Des. 846,101, which is a continuation of application No. 29/590,354, filed on Jan. 10, 2017, now Pat. No. Des. 806,216, which is a continuation of application No. 29/587,807, filed on Dec. 15, 2016, now Pat. No. Des. 821,973, which is a continuation of application No. 29/538,912, filed on Sep. 9, 2015, now Pat. No. Des. 761,400.

It should show:

(63) Continuation of application No. 29/769,312, filed on Feb. 4, 2021, now Pat. No. Des. 926,946, which is a continuation of application No. 29/747,233, filed on Aug. 20, 2020, now Pat. No. Des. 912,786, which is a continuation of application No. 29/719,734, filed on Jan. 7, 2020, now Pat. No. Des. 896,931, which is a continuation of application No. 29/706,139, filed on Sep. 18, 2019, now Pat. No. Des. 875,903, which is a continuation of application No. 29/679,571, filed on Feb. 7, 2019, now Pat.
